WILLIAM CARTER COMPANY, OF NEEDHAM HEIGHTS, MASSACHUSETTS, A COR-
PORATION OF MASSACHUSETTS.

YARN-CONTROL MECHANISM.

Application filed September 23, 1924. Serial No. 739,326.

This invention relates to yarn control for knitting machines, and more particularly to improved means for effecting a positive, controlled feed of the yarn or yarns to the needles of the machine, or to the needles and the immediately cooperating instrumentalities thereof, and in such a manner as to prevent press-offs in the event of yarn breakage or exhaustion.

In the accompanying drawings disclosing one embodiment of my invention:

Fig. 1 is a front elevation of the central and left portions of a circular knitting machine, shown as of the dial type, having my invention applied thereto;

Fig. 2 is a plan view taken from above the entire mechanism, with parts broken away;

Fig. 3 is a side elevation of the upper portion of the machine, showing the yarn feeding means and the upper stop motion head related thereto;

Fig. 4 is an end elevation of one set of feed wheels or rolls and closely associated parts;

Fig. 5 is a vertical section taken through a set of feed wheels or rolls such as shown in Fig. 4;

Fig. 6 is a detail view of a portion of a yarn guiding and stop motion actuating mechanism associated with each set of feed rolls or wheels;

Figs. 7, 8 and 9 are partially diagrammatic views indicating the operation of the mechanism and the relation of the positive feed to the stop motion and the let-off mechanism in preventing press-offs in the event of yarn failure or breakage;

Fig. 10 is a plan view, partially diagrammatic, upon a smaller scale than Fig. 2.

My invention may be applied to any desired type of knitting machine as, for example, either straight or rotary, and with the latter type it may be employed with a rotated needle cylinder or rotated cam cylinder. I have chosen to represent the invention as applied to a circular type of knitting machine having a rotated needle cylinder and a flat dial. I desire it to be understood that my invention is not limited to the disclosed or any other particular type of machine, although peculiarly cooperating with the circular type having a plurality of yarn feeds and with circular machines of the rib type.

This application is a continuation as to certain common subject matter of my co-pending application, Serial No. 633,140, filed April 19, 1923, now Patent #1,512,891, dated October 21, 1924.

Referring now to the drawings and particularly to Fig. 1 the bed plate of the machine is there indicated at 1 and is supported upon suitable uprights 2 extending from a base 3. The cam cylinder is indicated as a whole at 4 and the dial plate at 5. From said dial plate there is upstanding a central stationary support 6 extending through a cross head 7, itself supported from the bed plate 1 by suitable posts 8, 9.

From said bed plate there extends upwardly at the right in Fig. 1 a bracket 10 having an inwardly curved upper portion 11 at the inner end of which is supported a collar 12 in which is received and secured a central stationary upright 13 which at its lower end supports a portion of one stop mechanism indicated generally at 14.

Said stop motion 14, which will be hereinafter referred to as the lower stop motion, includes an upper ring or disc-like member 15, an intermediate ring 16 below said member 15 and having pivoted therein a number of vibratory members 17 provided with counter weights 18, the number of said vibratory members corresponding to the number of yarns or threads supplied to the needles. Below the intermediate ring 16 is a ring 19 over which the various yarns pass, being guided through the eyes 20, 21 of the pivoted vibratory members 17. Below said ring 19 is desirably positioned another ring 19^a over which the yarns pass and thence directly to the needles of the machine which are a relatively short distance therefrom, passing first through guides 19^b, one for each yarn.

The central upright 13 carries at an intermediate point a disc-like member 22 from which extend supports for the individual yarn packages here shown as rods 23 extending substantially radially and downwardly and terminating suitably to support each a yarn package 24 equalling in number the number of yarns or threads to be supplied to the knitting mechanism.

Above said member 22 there is secured to the central upright 13 a stationary head or casing 25, seen in Fig. 1 and upon a larger

scale in Fig. 3, and illustrated as somewhat conical in form at its upper portion and of a depth sufficient to receive a portion of the driving mechanism for the positive yarn feeding means and also to receive in its lower portion suitable stop mechanism, herein-after referred to as the upper stop mechanism and which may be of any well known form. Upon its upper surface said head or casing 25 is formed with a bearing 26 through which extends a horizontal shaft 27. Said shaft is supported at its outer end in a bearing 28 upon a bracket 29 carried at the upper end of a vertical rod or upright 30 rising from a bracket 31 itself supported on the machine framing.

The main drive shaft of the machine is indicated at 32 and has thereon fast and loose pulleys 33, 34 and at its inner end a bevel pinion 35 by means of which the needle cylinder is rotated. Suitable let-off mechanism is indicated as a whole at 33^a the same including a shiftable belt-fork 33^b and operating levers 33^c, 33^d adapted to be actuated to shift the belt through suitable connections, including the chain 33^e.

Driven from said main drive shaft 32 through suitable connections, not necessary to indicate herein, is a vertical shaft 36 at the upper end of which, at the upper left portion of Fig. 1, is fast a bevel pinion 37, indicated by dotted lines, and meshing with a similar pinion 38 fast at the outer end of the horizontal shaft 27 already mentioned and which is thereby rotated at a suitable speed.

At the inner end of said horizontal shaft 27, within the head 25, is fast a bevel pinion 39 seen in dotted lines in Fig. 2 and which meshes with teeth upon the upper face of a plate gear 41 rotatably supported upon the upright 13 within the casing 25. Said plate gear is formed upon its lower face near its outer edge with an annular series of teeth 45 which mesh with and drive a series of bevel pinions 46, indicated in dotted lines in Fig. 2. Said pinions 46, corresponding in number to the number of yarns or threads fed to the machine and hence to the number of yarn or thread packages 24, are arranged in a circular series, each being supported upon the inner end of a substantially radial horizontal shaft 47 extending upwardly through the head or casing 25 and provided with suitable bearings therein. Each of said shafts 47 extends outwardly through a bracket 49, Figs. 1, 2, 3 and 10, suitably supported as by means of a fixed stud or rod 50. Each stud or rod 50 lies in substantial parallelism with its shaft 47 and at its inner end is secured as by a set screw 52 in the head or casing 25 or an extension thereof.

Upon the outer end of each shaft 47 beyond its bracket 49 is fast one feed roll or wheel 53 of a set of such rolls or wheels.

Any desired plurality of such feed members may be employed and herein I have shown each set as including three thereof but within the scope of my invention a greater or less number may be employed. As best seen in Fig. 5, said feed rolls or wheels are preferably conical or tapering and their outer surfaces may be of any suitable nature but desirably fluted or toothed lengthwise in the manner shown. The teeth or flutes 54 of each roll 53 may mesh throughout their entire length or any suitable portion only of their length with the teeth or flutes 55 of a similar lower roll or wheel 56. As shown, the mesh is somewhat deeper at the larger diameter ends of the rolls. Said lower roll or wheel 56 is rotatably mounted upon a stud shaft 57 carried at the outer end of an arm 58, see Fig. 4, of a bell crank 59 itself pivoted at 60 upon the bracket 49 and having an arm 61 extending upwardly in general parallelism with said bracket 49. At its upper end said arm 61 receives a pin 63 supported at its inner end in the bracket 49. The outer end of said pin 63 is screw threaded to receive an adjusting nut 64 and a lock nut 65 by means of which the position of the bell crank 59 and the roll or wheel 56 may be very accurately determined and in this manner the longitudinal extent and the depth of meshing of the roll 56 and the roll 53 accurately controlled. A coil spring 66 bearing intermediate the bracket 49 and the arm 61 of the bell crank tends to move said arm 61 outwardly.

Above the roll 53 is provided, in the present form of my invention, a third feed roll or wheel 67 having teeth or flutes 68 and mounted for rotation from or by the roll 53. The teeth or flutes of said roll 67 mesh with those of said roll 53 similarly as do the teeth or flutes 55 of the lower roll 56. Said upper roll 67 is adjustably supported in a manner similar to said lower roll, being loosely mounted upon a stud 69 at the outer end of one arm 70 of a bell crank 71 pivoted as at 72 upon the bracket 49. The other arm 73 of said bell crank extends downwardly and at its lower end is provided with an opening through which passes the pin 74 supported at its inner end by the bracket 49. At its outer end said pin 74 is threaded to receive an adjusting nut 75 and a lock nut 76 whereby the meshing relation of the upper roll 67 and the roll 53 may be accurately controlled. A coil spring 77 similar to the spring 66 tends to move the arm 73 outwardly. The upper and the lower rolls or wheels are thus positively rotated from or by the central roll 53, herein through the teeth or flutes upon said members, but if desired separate pinions may be provided for that purpose.

The respective sets of feed rolls or wheels are supported at a relatively short distance 130

above the respective yarn packages 24 and preferably not directly in a vertical line with the axis of said packages but somewhat spaced laterally from such line. As clearly seen in Fig. 10, each set of feed wheels or rolls herein, but not necessarily, lies to one side of its yarn package, in such manner that the yarn may be introduced between the wheels or rolls in a lateral direction. If desired, and as shown in Figs. 1 and 10, I provide a series of arms 78 projecting radially from the central support 13 and each terminating in an eye or guide 79 herein constituting a knot catcher but of sufficient size to permit the ready passage of the thread or yarn with sufficient freedom to allow for the ballooning or lateral motion thereof. Said eye or opening at the end of an arm 78 desirably is itself directly in line vertically with the axis of its yarn package and accordingly somewhat laterally spaced from the corresponding set of feed wheels.

Intermediate the eye or guide of each arm 25 78 and the positive feeding means, herein the corresponding set of feed rolls or wheels, I provide means for variably guiding the yarn to said positive feeding means and for initiating the action of a stop motion, herein contained in the lower portion of the head 25, upon exhaustion of the yarn, or breakage thereof between the yarn package and the associated positive feeding means. Accordingly, as best seen in Figs. 1, 3 and 4, there is adjustably mounted at the lower end of the bracket 49 or in an extension 49^a thereof a sleeve-like member 80 constituting a bearing for a rock shaft or wire 81 forming part of the trip mechanism which is adapted to control or initiate the action of the internal mechanism of the stop motion within said casing 25.

At its outer end each such rock wire 81 is formed with a finger 82 which, when the yarn is feeding normally, is in upright position and cooperates with a fixed finger 83 extending upwardly from said sleeve 80, said fingers together constituting in their normal position an eye or guide for the yarn passing to the positive feeding means such as the wheels or rolls herein shown.

The yarn guiding portions of said fingers 82, 83 are positioned relatively close to the bight or meshing line of the feed rolls or wheels 53, 56 and so that the yarn from the package after passing through the guide in the arm 78, if provided, may pass in a lateral direction through said fingers and directly to said feed members.

60 Also said fingers 82, 83 are adjustable, herein manually, so as to permit their yarn guiding portions to be shifted along the meshing line of the feed members 53, 56. By loosening the clamp screw 80^a, Figs. 3 and 4, provided for holding each sleeve-like

member 80 in adjusted position in its bracket 49, said member 80 and the fingers 82, 83 carried thereby may be shifted to effect the described adjustment.

As well shown in Fig. 3 and also in Figs. 70 4 and 6, each rock wire 81 at its inner end is supported for rocking movement in a suitable bracket 25^a depending from the head 25 or casing 25.

Near its inner end said rock wire 81 has fixed to it a release finger 81^a having a portion 81^b extending in substantial parallelism with said rock wire. Said release finger 81^a when in normal position, supports the outer end 84 of a suitably weighted drop finger or 80 like trip member 85 the latter being pivotally supported within the casing or head 25 and cooperating in a well known manner with the stop mechanism therein to cause the same to act to operate the left-off mechanism 85 and stop the machine.

Upon the exhaustion of the yarn from any package or upon break in the yarn between the package and the positive feeding means therefor the movable finger 82 will fall from its vertical position shown in Fig. 3, rocking the shaft or wire 81 and causing the release finger 81^a also to fall. Said falling or removal of said release finger 81^a withdraws the support of the trip member 85 which moves vertically downward thereby actuating the mechanism within the head 25 so as to trip the same and causing or allowing the let-off mechanism to operate to shift the belt from the fast to the loose pulley and also to apply a brake if provided.

Any suitable connections may be provided intermediate the upper stop motion in the head 25 and the left-off mechanism whereby the belt fork 33^b may be moved to stop the machine. As best seen in Figs. 8 and 9, partially diagrammatically, said connections include a movable pin 86 which is caused to move laterally, viewing Fig. 8, in the known manner, when the upper stop mechanism, in the head 25, is tripped. Said pin 86 carries at its lower end an outwardly projecting finger 87 cooperating with a lug 88 fast at the upper end of a rod or shaft 89 rotatably supported in a suitable bearing 90 carried by the machine framing. Movement of said pin 86 will produce turning movement of said rod 89 thereby causing the finger 91 at the lower end of the latter to be moved out of the path of the stud 92 carried by the rotatable cam 93, thus leaving said cam free to turn upon its pivot 94.

Cooperating with said cam is a vertically movable stop 95 supported in a suitable bracket 96 and pressed upwardly by a coil spring 97 bearing between a shoulder on said stop member 95 and the lower portion of said bracket 96. At its lower end said stop member 95 is formed as a rod 98 projecting below the bed plate 1 and having secured at

its lower end an arm 99. When the rod 98 is moved upwardly by the spring 97 the inner end of said arm 99 comes within the path of a series of pins, one of which is indicated at 100 in Fig. 9 near the periphery of the gear 101 for actuating the needle cylinder. At its opposite end said arm 99 has secured thereto the inner end of the chain or like member 33^a already described and whereby the lever 33^a may be moved to shift the belt, see Fig. 1.

Referring to Fig. 7, the yarn 102 from any given package 24 leads upward through the corresponding guide 79, thence upwardly and laterally through the combined variable yarn guiding and stop motion actuating means 82, 83, and thence laterally in substantially a horizontal direction between the lower feed rolls or wheels 56 and 53. At the side of said rolls opposite to said means 82, 83 is preferably provided a yarn guide 105, see also Figs. 3 and 4, adjustably supported on the extension 49^a of the bracket 49 so as to be shiftable, herein manually, along the bight 20 of said rolls 56 and 53 similarly as the combined guiding and stop-motion actuating means 82, 83 is adjustable. Said guide, as illustrated, has a slotted portion 106 through which passes a clamp screw by loosening which said guide may be adjusted longitudinally and vertically as desired.

After passing through said adjustable guide 105 the yarn 102 is then led between the upper feed rolls or wheels 53 and 67, and thence preferably through another adjustable guide 107 similarly supported upon the bracket 49 as said guide 105 so as to be shiftable manually along the bight of said rolls. Thence the yarn 102, positively fed at variable speeds by said set of wheels or rolls, extends upwardly over the upper guide or tension arm 108 suitably supported at the upper end of the central upright 13 and whence it passes downwardly, through a guide 109 if desired to the lower stop mechanism already described.

Because of the provision, intermediate each yarn package and the positive feeding means pertaining thereto, of means for initiating the operation of a stop mechanism in the event of failure or exhaustion of the yarn, or breakage therein between the points mentioned, the over-all height of the machine may be materially reduced. Ordinarily the upper yarn guide or tension arm, such as the member 108 herein, must be located at a comparatively great distance above the feed means, generally at least three feet, in order to provide sufficient length of yarn between the feed means and the needles to tend to prevent a press-off of the yarn in the event of yarn exhaustion or breakage. Such excess height of the machine, in addition to decreasing its compactness, adds to the cost of manufacture

and makes the upper parts of the machine less easily accessible to the operative. By the disclosed provision of means adjacent the positive yarn feeding means, and preferably between the latter and the yarn package, for initiating the operation of mechanism for stopping the machine the height of said upper guide and consequently the length of yarn necessary between the feeding means and the needles may be reduced by approximately one half. Since the stopping of the machine is initiated by the movement of a member, herein the combined yarn guiding and drop wire 82 before the run-out or broken yarn end reaches the feeding means, the machine will stop before such end reaches the needles, or even reaches the lower stop mechanism disclosed, and in some instances before such end has passed the feed means.

From the foregoing it will be understood that my invention provides a combined positive variable yarn feeding and press-off preventing mechanism including means for variably, positively feeding the yarn, adjustable means for guiding the yarn thereto and means adjacent or forming part of said guiding means for initiating the stopping of the knitting machine before a broken or exhausted yarn end has appreciably passed said feeding means thereby preventing press-offs and decreasing by at least one-half the length of yarn necessary between said feeding means and the needles.

My invention is not limited to the illustrative embodiment thereof disclosed.

Claims:

1. In a knitting mechanism including one or more yarn packages corresponding in number to the number of yarns to be supplied, knitting instrumentalities to which the yarn or yarns are to be fed, and a stop motion for stopping the operation of the mechanism, the combination of sets of conical, longitudinally toothed or fluted feed wheels or rolls, one adjacent each yarn package, a movable finger in the path of each yarn intermediate its yarn package and the corresponding set of feed wheels or rolls, said finger operatively connected with said stop motion and normally maintained in inoperative position during proper feeding of the yarn but movable to initiate the action of said stop motion in response to failure of the yarn or breakage thereof at a point between the package and said feed wheels or rolls, and a normally stationary finger cooperating with said movable finger to guide the yarn to said feed wheels or rolls, the yarn guiding portions of said fingers being adjustable to vary the point of feed of the yarn with respect to said feed wheels or rolls thereby to vary the rate of yarn feed.

2. In a knitting mechanism including one or more yarn packages corresponding in

- number to the number of yarns to be supplied, knitting instrumentalities to which the yarn or yarns are to be fed, and a stop motion for stopping the operation of the mechanism, the combination of sets of conical, longitudinally toothed or fluted feed wheels or rolls, one adjacent each yarn package, a movable finger in the path of each yarn intermediate its yarn package and the corresponding set of feed wheels or rolls, said finger operatively connected with said stop motion and normally maintained in inoperative position during proper feeding of the yarn but movable to initiate the action of said stop motion in response to failure of the yarn or breakage thereof at a point between the package and said feed wheels or rolls, and adjustable means cooperating with said finger normally to maintain the same in said inoperative position and to guide the yarn to said feed wheels or rolls at points variable longitudinally thereof thereby to vary the rate of yarn feed.
3. In a knitting organization including a source of yarn supply, knitting instrumentalities to which said yarn is to be fed, mechanism for operating said instrumentalities, and a stop motion for stopping said mechanism, the combination of means for positively, variably feeding said yarn, and means positioned intermediate the yarn supply and said feeding means for initiating the action of the stop motion and adapted variably to guide the yarn in its passage to said feeding means, so as to vary the rate of feed of the latter, and whereby the knitting operation will be suspended as an immediate consequence of the exhaustion of the yarn or the breakage thereof between the yarn source and said feeding means.
4. In a knitting organization including a source of yarn supply, knitting instrumentalities to which said yarn is to be fed, mechanism for operating said instrumentalities, and a stop motion for stopping said mechanism, the combination of rotary members for feeding the yarn at rates variable according to the position longitudinally thereof at which the yarn is fed, a drop member for causing said stop motion to function, said member being constructed and arranged as an eye or guide adjacent said rotary members and adjustable lengthwise of the latter to vary the rate of feed of the yarn guided to them by said drop member and cooperating means whereby the yarn normally retains said drop member in its raised or inoperative position.
5. In a knitting organization including a source of yarn supply, knitting instrumentalities to which said yarn is to be fed, mechanism for operating said instrumentalities, and a stop motion for stopping said mechanism, the combination of a set of rotary
- members for positively feeding the yarn, and means close to said rotary members for initiating the action of the stop motion and normally functioning as a guide for the yarn, and held out of mechanism stopping position thereby during proper yarn feeding, whereby the overall height of the knitting organization may be materially reduced without danger of the occurrence of a press-off of the yarn in the event of yarn exhaustion or breakage on the way to or upon emergence from said rotary members.
6. A combined positive yarn feed and press-off preventing stop mechanism for knitting machines comprising in combination in a knitting organization, means to support one or more yarn packages, positive yarn feeding means adapted to act continuously to feed the yarn, a stop motion for the machine, and means intermediate each yarn package and its positive feeding means for variably guiding the yarn to the latter to vary the rate of yarn feed, said yarn guiding means being constructed and arranged to initiate the action of said stop motion upon failure or breakage of the yarn between the yarn package and said positive feeding means and whereby the over-all height of the knitting machine may be materially reduced.
7. Positive yarn feeding and press-off preventing mechanism for knitting machines equipped with a stop motion, comprising in combination, a support for one or more yarn packages, a set of conical feed wheels for each yarn package for positively feeding the yarn therefrom, a yarn guide for each package, vertically spaced therefrom, and means intermediate said yarn guide and the respective set of feed wheels for guiding the yarn between said wheels at points variable lengthwise thereof, said means including a drop wire adapted to function upon breakage or exhaustion of the yarn between the package and the set of feed wheels therefor to initiate the operation of the stop motion thereby to stop the machine before the broken or exhausted yarn end reaches the needles, and whereby the over-all height of the knitting machine may be materially reduced.
8. A combined positive yarn feed and press-off preventing mechanism for knitting machines comprising in combination, in a knitting organization, means to support one or more yarn packages, positive yarn feeding means adapted to act continuously to feed the yarn at variable speeds, and a variable yarn guiding device intermediate each package and the yarn feeding means, said guiding device constituting also a movable part for initiating the action of a stop motion upon exhaustion of the yarn or breakage thereof between said package and said

positive feeding means, and whereby the over-all height of the knitting machine may be materially reduced.

9. A combined positive yarn feed and press-off preventing mechanism for knitting machines comprising in combination, in a knitting organization, means to support one or more yarn packages, positive yarn feeding means adapted to act continuously to feed the yarn at variable speeds, a guide for each yarn axially above the package and a second yarn guiding device spaced laterally from said first guide and sufficiently distant from said feeding means to accommodate the ballooning or other local irregularities of delivery of the yarn off its package and thus to permit the consequent fluttering of the yarn at said feeding means, said guiding device constituting also a movable part for initiating the action of a stop motion upon exhaustion of the yarn or breakage thereof between said package and said positive feeding means.
10. In a knitting organization including a source of yarn supply, knitting instrumentalities to which said yarn is to be fed, mechanism for operating said instrumentalities, and a stop motion for stopping said mechanism, the combination of a set of toothed, intermeshing, driven feed rolls for positively feeding the yarn, and means close to said feed rolls for initiating the action of the

stop motion and normally functioning as a guide for the yarn and held out of mechanism stopping position by the yarn during proper yarn feeding, whereby the overall height of the knitting organization may be materially reduced without danger of the occurrence of a press-off of the yarn in the event of yarn exhaustion or breakage on the way to or upon emergence from said feed rolls.

11. In a knitting organization including a source of yarn supply, knitting instrumentalities to which said yarn is to be fed, mechanism for operating said instrumentalities, and a stop motion for stopping said mechanism, the combination of a set of toothed, driven feed rolls for positively feeding the yarn, and means close to said feed rolls and mechanically supported in the knitting organization, for initiating the action of the stop motion and normally functioning as a guide for the yarn and held out of mechanism stopping position by the yarn during proper yarn feeding, whereby the overall height of the knitting organization may be materially reduced without danger of a press-off of the yarn in the event of yarn exhaustion or breakage on the way to or upon emergence from said feed rolls.

In testimony whereof, I have signed my name to this specification.

WILLIAM P. DRUMHELLER.
